UNITED STATES PATENT OFFICE.

CHARLES H. TOWER, OF HOLYOKE, MASSACHUSETTS.

VENTILATION SYSTEM.

Application filed July 23, 1920. Serial No. 398,538.

To all whom it may concern:

Be it known that I, CHARLES H. TOWER, a citizen of the United States of America, residing at 56 Fairfield Ave., Holyoke, in the county of Hampden and State of Massachusetts, have invented certain new and useful Improvements in Ventilation Systems, of which the following is a specification.

This invention relates to improvements 10 in ventilating systems and its leading object is to provide a ventilating system and apparatus whereby a constant inflow of fresh air and outflow of used air can be produced in a building without the necessity 15 of using motor driven fans or the like.

The invention is embodied in a ventilating apparatus which includes a rotary hooded intake adapted to be positioned on the roof of a building and a warm air conduit 20 having communication with said intake to deliver the warm air of the building in the direction of the wind and the cold air conduit having communication with said intake to receive cold air under wind pressure, 25 the warm air conduit having its intake at the top of the building or at the top of each room thereof and the cold air conduit having its outlet at the bottom of the building or at the bottom of each room thereof.

30 With the above and other objects in view this invention relates to certain new and useful constructions, combinations and arrangements of parts, clearly described in the following specification and fully illustrated 35 in the accompanying drawings in which:

Figure 1 is a vertical sectional view taken through a building equipped with my improved ventilating apparatus.

Figure 2 is a similar view taken through 40 a building provided with a series of floors and cold air and warm air conduits having a plurality of openings.

Fig. 2^a is a detail sectional view of the warm air conduit showing a valve.

45 Figure 3 is a detail sectional view through the cold air conduit showing the deflecting valve for causing the cold air to flow into the building.

Referring to the accompanying drawings 50 5 designates a building having a floor 6 and a roof 7 and side walls 8 and which may be of any construction. On the roof 7 a rotary intake 9 is mounted to work upon the base support 10. This rotary intake is provided with the usual wind control vane 11 and with a warm air outlet or opening 12

located on the same side of the intake member as the vane 11 so that the said outlet 12 will always face in the direction the vane 11 faces away from the wind. The member 9 60 is provided with the usual hood 13 and with a cold air intake opening 14 which faces in the direction opposite to the direction of the warm air outlet 12, that is toward wind. The opening 14 is provided with suitable 65 baffles or dust retarding bars 15 and which may be adjusted for the different periods of the year or conditions of the surrounding atmosphere.

An elbow 16 is mounted within the middle of the member 9 and the upper end of said elbow 16 has communication with the opening 14 and the lower end or vertical leg of the elbow 16 has a swivel connection 70 at 17 with the upper end of the cold air 75 conduit 18.

The cold air conduit 18 may be of any suitable construction and extend along the faces of the building ceiling and the walls thereof or between the walls thereof and is 80 preferably insulated by asbestos or the like to prevent exchange of heat between the room or building and the inflowing cold air. The warm air conduit 19 has communication at its upper end with the base 10 on 85 which the rotary member 9 works and may be arranged against the walls of the building or built in said walls. The cold air conduit 18 is provided with an outlet 18' located at the lower end thereof and which is disposed at a point slightly above the level of the floor of the building while the warm air conduit 19 is provided at its lower end with an intake 19^a, located near the ceiling 90 of the room or the roof of the building, so as to receive warm air from the warm air strata or zone which exists in a heated room. 95

The cold air conduit 18 is equipped with a movable deflecting valve 20, whereby downflowing cold air will be deflected into 100 a room, and is also provided with a damper 21, whereby the amount of the air coming into a room may be regulated at will.

The warm air conduit 19 is provided with a movable deflecting valve 20^a and a damper 105 21^a, for similar purposes.

When the building is provided with a series of floors and superimposed rooms the cold air conduit is provided with an outlet into each room and the warm air conduit 110 is provided with an inlet located in the upper part of each room.

The intake conduit is insulated by the insulating material 18^a so that the inflowing air will not be heated by the heat of the room, and a thermo circulation will be maintained by reason of the displacement of the warm air in the room or rooms by the inflowing cold air which is not preheated during its flow through the intake conduit.

The two conduits thus provide, in conjunction with the chamber or chambers of the building, a path for the constant circulation of air. The warm air is permitted at all times when the intake opening or openings are not closed to flow upwardly, while the cold air, which is heavier than the warm air, is likewise permitted to flow downwardly, thus providing a non-forced natural circulation of fresh air from the outside through the building, the extent of which may be controlled at will. When a sharp wind is blowing into the fresh air intake the velocity of flow of the incoming air will be accelerated, thus accelerating the velocity of flow of the used air in the building, as will be readily understood.

My invention provides means for ventilating a building, without creating dangerous drafts, and without employing motor driven fans or the like.

Having described my invention I claim:

A ventilating system consisting of the

combination of a building having a plurality of superimposed compartments of a cold air pipe having an outlet opening near the floor of each compartment and having its wall insulated against the transference of the heat in the compartments to the cold air flowing therein, a stationary bearing on the building, a ventilator mounted to rotate on said bearing and provided with an intake opening on one side thereof and a wind vane on the opposite side to maintain the intake in wind-facing direction an elbow conduit having rotatable connection with the upper end of the cold air pipe and permanent connection with the intake, said ventilator having a warm air outlet facing in the direction of the wind vane, and a warm air pipe having a warm air inlet near the ceiling of each compartment and an outlet discharging into the warm air outlet of the ventilator, whereby a thermo-circulation is maintained in the compartments and the velocity of this circulation will be accelerated by wind pressure upon the cold air pipe, and upwardly inclinable and inwardly opening deflecting valves for closing and opening said cold air outlets.

Signed by me at Holyoke, Mass., Jan. 17th, 1920.

CHARLES H. TOWER.
